PACKAGE DISPENSER

Edward S. Black, Chicago, Ill.

Application July 3, 1952, Serial No. 20,458

Term of patent 14 years

(Cl. D52--2)

To all whom it may concern:

Be it known that I, Edward S. Black, a citizen of the United States, and a resident of Chicago, in the county of Cook and State of Illinois, have invented a new, original, and ornamental Design for a Package Dispenser, of which the following is a specification, reference being had to the accompanying drawing, forming a part thereof.

Fig. 1 is a perspective view of a package dispenser, embodying my new design;

Fig. 2 is a side elevational view of the package dispenser shown in Fig. 1; and

Fig. 3 is a top plan view of the package dispenser.

I claim:

The ornamental design for a package dispenser, as shown.

EDWARD S. BLACK.
